UNITED STATES PATENT OFFICE.

SAMUEL M. RIKER, OF CHESTER, NEW JERSEY.

BELT BUCKLE.

1,406,282.

Specification of Letters Patent. Patented Feb. 14, 1922.

Application filed May 6, 1921. Serial No. 467,366.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in belt-buckles; and, the present invention is in the nature of improvements in the form of belt-buckle described and claimed in another application filed by myself, contemporaneously herewith, the present invention comprising in combination with an ornamental face-plate or buckle-body, a pair of clamping elements or members, one of which is pivotally connected 20 with the buckle-body, and the other clamping element or member being pivotally connected with the clamping element or member which is connected with the buckle-body, said clamping elements or members being 25 adapted to be brought into active engagement with each other, and both said elements or members co-operating with each other to bring the belt-body into a firmly clamped relation with the back of the main 30 face-plate or body of the buckle.

35 The present invention has for its principal objects to provide a novel and simply-constructed belt-buckle comprising a pair of clamping elements, one clamping element 40 being pivotally connected with the buckle-body, and the other clamping element being pivotally connected with said first-mentioned clamping element, but said clamping elements being adapted to engage each other 45 during the clamping operation with the belt-body, the two clamping elements or members co-operating with each other to provide a more secure and positive clamping action against the belt-body, and the arrangement and construction of the two co-operating clamping elements or members being such, so that the clamp-means will readily accommodate itself in operation to various thicknesses of belt-bodies with 50 which the buckle may be employed, without unduly straining the parts of the buckle,

while providing a doubly locked and adequate gripping or clamping effect when in use.

Other objects of the present invention not 60 at this time more particularly enumerated will be clearly understood from the following detailed description of the present invention.

With the various objects of the present invention in view, the said invention consists, primarily, in the novel belt-buckle herein-after set forth; and, the said invention consists, furthermore, in the novel arrangements and combinations of the various devices and parts, as well as in the details of the construction of the said parts, all of which will be more fully described in the following specification, and then finally embodied in the clauses of the claims which 75 are appended to and which form an essential part of the said specification.

The invention is clearly illustrated in the accompanying drawings, in which:—

Figure 1 is a front face view of a belt-buckle showing one embodiment of the principles of the present invention, operatively associated with a belt-body.

Figure 2 is a rear face view of the buckle, and portions of the belt-body to which it is 85 attached; and Figure 3 is a side edge elevation of the same.

Figure 4 is a central longitudinal vertical section, on an enlarged scale, of the belt-buckle, and portions of the belt-body to 90 which it is attached; and Figure 5 is a transverse vertical section of the same, said section being taken on line 5—5 in said Figure 4, looking in the direction of the arrow *x*.

Similar characters of reference are employed in all of the said above described views, to indicate corresponding parts.

Referring now to the several figures of the drawings, the reference-character 1 indicates the complete belt-buckle, the same 100 comprising a main member or buckle-body consisting of a face-plate 2, which is preferably outwardly convexed, and is provided along its longitudinally extending edges with rearwardly projecting side-flanges 3. 105 The said side-flanges 3 are provided at or near one end of the buckle-body with perforations 4, or similar means, providing suitable journal or pintle-receiving bearings for the purposes to be presently more fully 110 set forth.

The reference-character 6 indicates a

transversely extending member or bar of a loop-element 5, from which extends outwardly beyond the adjacent end of the buckle-body, a loop-portion 7 of any suitable configuration. The said member or bar 6 is provided at its opposite ends with journal-lugs or pintles 8, which are suitably disposed in the previously-mentioned bearings 4 of the side-flanges 3, thereby pivotally connecting said loop-member between the said side-members, and spaced rearwardly from the back or inner face of the face-plate 2. Extending upwardly from said transversely extending member or bar 6, and also spaced rearwardly from the back or inner face of the face-plate 2 is a cam-member, or gripping or clamping element, as 9, said member or element being provided with a laterally and outwardly projecting convolution or convolutions 10, substantially as shown, and for the purposes to be presently more fully specified.

The reference-character 11 indicates another transversely extending member or bar, provided at its opposite ends with suitably bent portions, as 12, said portions forming pivot-eyes which encircle portions of the member or bar 6 of said loop-element 5, and whereby the member or bar 11 is pivotally connected with the member or bar 6 of said loop-member, as will be clearly evident from an inspection of Figures 2, 4 and 5 of the drawings, all being suitably arranged for pivotally or movably disposing a suitably convexed belt-body-gripping or clamping plate, as 13, which extends in a forward direction from said member or bar 11 directly above and over the above-mentioned cam-member, or gripping or clamping element 9. As will be evident from an inspection of Figure 4 of the drawings, the said plate 13 is also provided with a laterally and downwardly projecting convolution or convolutions, as 14, and with a laterally and upwardly projecting convolution or convolutions, as 15.

The reference-character 16 indicates a belt-body of any suitable thickness, and in attaching this belt-body to the buckle, one end 17 is looped and fastened about the free end of said loop-portion 7, so as to have a fixed relation thereto. In applying the belt and buckle to the waist of the wearer, the belt-body 16 is carried around the waist, and the free end 18 of the belt-body is inserted between the back or inner face-plate 2 and the outer corrugated or ribbed face of the belt-gripping or clamping plate 13. As the belt-body is drawn up tightly around the waist of the wearer, in the direction of the arrow x , see Figure 4, the pull or tension upon the loop-member 7, swings the latter in a direction toward the back or inner face of the face-plate 2, thereby moving the convolution or rib 10 of the cam-member or gripping or clamping element 9 forcibly into

contact and over the inwardly or downwardly projecting convolution or rib 14 of the plate 13, the convolution or rib 10 in passing over said convolution or rib 14 passing back of the same with an audible and positive snap, so as to positively lock the parts in place, and firmly forcing the upwardly projecting convolution or rib 15 into biting or gripping relation with the belt-body, whereby the latter is firmly gripped between the buckle-body and the clamping or gripping plate 13, and the free end of the belt is held unyieldingly against withdrawal from such engaged relation to the buckle.

Owing to the peculiar shape, position and arrangement of the serrated or convoluted clamping or gripping plate 13, relative to the serrated or convoluted cam-member or bar of the loop-member 7, the co-relation of said parts are rendered more or less yieldable, so that the buckle-body may be positively secured to belt-bodied of greater or less thickness than the usual thickness without any loss of clamping effect, the snap-lock effect of the parts positively securing the belt and buckle in their adjusted relation about the waist of the wearer against any accidental displacement, as will be clearly understood. To release the parts from the gripped or clamped relation with the belt-body, all that is necessary is to swing the loop-member 7 in the direction of the arrow y , indicated in Figure 3 of the drawings.

Of course I am aware, that some changes may be made in the general arrangements and combinations of the several devices and parts, as well as in the details of the construction of the said parts, as set forth in the foregoing specification, and as defined in the clauses of the claims which are appended thereto. Hence, I do not limit my present invention to the exact arrangements and combinations of the various devices and parts as described in the said specification, nor do I confine myself to the exact details of the construction of the said parts, as illustrated in the accompanying drawings.

I claim:

1. A belt-buckle comprising a buckle-body, combined with a loop-element, and a belt-body gripping or clamping element, said loop-element being pivotally connected with said buckle-body, and said belt-body gripping or clamping element being pivotally connected with said loop-element, said loop-element comprising a transversely and upwardly and rearwardly extending member, and means connected with the latter for forcing said belt-body gripping or clamping element into gripping or clamping engagement with a belt-body.

2. A belt-buckle comprising a buckle-body, combined with a loop-element, and a belt-body gripping or clamping element,

- said loop-element being pivotally connected with said buckle-body, and said belt-body gripping or clamping element being pivotally connected with said loop-element, said 5 loop-element comprising a transversely and upwardly and rearwardly extending member, a convolution extending from said latter member, and a convolution extending from said belt-body gripping or clamping 10 element with which the convolution of said transversely and upwardly and rearwardly extending member is adapted to be brought into locked engagement to force said belt-body gripping or clamping element into 15 gripping or clamping engagement with a belt-body.
3. A belt-buckle comprising a face-plate and longitudinally and rearwardly extending side-members, a loop element pivotally 20 connected with said side-members, said element comprising a transversely and upwardly and rearwardly extending member, a convolution projecting from said member, a belt-body gripping or clamping element 25 pivotally connected with said loop-element, said gripping or clamping element comprising a convexed gripping or clamping plate, convolutions extending, respectively downwardly and upwardly from said plate, the 30 convolution of said transversely and rearwardly and upwardly extending member of the loop-element being adapted to be forcibly brought into locked engagement with the downwardly extending convolution of 35 the gripping or clamping plate of said gripping or clamping element for forcing the upwardly extending convolution of said plate into gripping or clamping relation with a belt-body.
4. A belt-buckle comprising a face-plate and longitudinally and rearwardly extending side-members, combined with a loop-ele- 40
- ment, and a belt-body gripping or clamping element, said loop-element being pivotally disposed between said side-members adjacent to one end of said face-plate, and said belt-body gripping or clamping element being pivotally connected with said loop-element, and means connected with said loop-element adapted to be brought into locked 45 engagement with said belt-body gripping or clamping element for forcing said gripping or clamping element into gripping or clamping engagement with a belt-body, and also locking said elements against accidental displacement. 50
5. A belt-buckle comprising a face-plate and longitudinally and rearwardly extending side-elements, combined with a loop-element, and a belt-body gripping or clamping element, said loop-element being pivotally disposed between said side-members adjacent to one end of said face-plate, and said belt-body gripping or clamping element being pivotally connected with said loop-element, said loop-element comprising a transversely extending cam-member, and said belt-body gripping or clamping element comprising a convexed gripping or clamping plate, and means connected with said 60 cam-member and with said plate adapted to be forcibly brought into interlocked retaining engagement against accidental displacement, and for forcing said plate into gripping or clamping engagement with a belt- 65 body. 70
- In testimony, that I claim the invention set forth above I have hereunto set my hand this 5th day of May, 1921.
- SAMUEL M. RIKER.
